Fig. 3.

Fig. 4.

Fig. 5. 17³, 16

A technical line drawing of a mechanical component, likely a piston or valve assembly. The drawing is labeled 'Fig. 8.' in a large, stylized font at the top left. Various parts are labeled with numbers: 124 at the top left, 106 at the top right, 101 and 108 at the top right, 144 at the top center, 150 at the top center, 39 and 105 on the left side, 96 at the bottom left, and 140 at the bottom right. The drawing shows a central circular feature with a textured or porous appearance, surrounded by a hatched area and various mechanical supports and connecting rods.

DRILLING APPARATUS

Win W. Paget, Michigan City, Ind., assignor to
 Sullivan Machinery Company, a corporation of
 Massachusetts

Application December 5, 1940, Serial No. 368,693

5 Claims. (Cl. 255—45)

This invention relates to drilling apparatus, and more particularly to improved feed control means for drills of the rotary type.

An object of this invention is to provide an improved drilling apparatus. Another object is to provide an improved feed control means for a drilling apparatus. Still another object is to provide a rotary type drilling apparatus having improved feeding means and feed control means responsive to the resistance to rotation of the drill bit for controlling the feeding pressure. A further object is to provide in a rotary type drilling apparatus an electric motor for rotating the drill bit, and improved means for controlling the feeding of the drill bit and having means responsive to the current drawn by said bit rotating motor for effecting such control. Another object is to provide with an improved fluid actuated feeding means for a rotary drilling apparatus a valve means for controlling the flow of fluid relative to said feeding means and an electromagnet connected in the circuit with an electric driving motor for the drilling apparatus and operative for controlling said valve means. Still another object of this invention is to provide an improved electromagnetically controlled valve means responsive to the variations in load on the drill bit rotating motor for controlling automatically the feeding means. Another object is to provide an improved valve means controlled by an electromagnet that is connected in the circuit with an electric bit rotating motor and continuously urged by the magnetic force of said electromagnet during the operation of said motor in a direction to reduce the supply of fluid to, if moved far enough, to vent fluid from the fluid actuated feeding means for the drill bit. Other objects and advantages of the invention will, however, hereinafter more fully appear.

In the accompanying drawings there is shown for purposes of illustration one form which the invention may assume in practice.

In these drawings:

Figs. 1 and 2 taken together constitute a view in longitudinal vertical section through an illustrative embodiment of the improved drilling apparatus.

Fig. 3 is an enlarged cross sectional view taken on the line 3—3 of Fig. 1.

Fig. 4 is an enlarged cross sectional view taken on the line 4—4 of Fig. 1.

Fig. 5 is a detail view in longitudinal vertical section taken substantially on line 5—5 of Fig. 4.

Fig. 6 is an enlarged detail sectional view taken

on the same plane as Fig. 3, showing the valve means.

Fig. 7 is a view similar to that of Fig. 6, but showing the valve means in a different position.

Fig. 8 is a detail sectional view taken substantially on line 8—8 of Fig. 3.

Fig. 9 is a detail sectional view taken substantially on line 9—9 of Fig. 3.

Fig. 10 is a detail sectional view taken substantially on line 10—10 of Fig. 3.

Fig. 11 is a diagrammatic view showing the control of fluid relative to the fluid actuated feeding means for the drilling apparatus.

In the illustrative embodiment of the invention there is shown an improved drilling apparatus of the rotary type adapted for use with core or plug type bits in drilling rock or other such material. The drilling apparatus is generally similar to that disclosed in my copending application Serial No. 322,267, filed March 5, 1940, now Patent No. 2,288,543, patented June 30, 1942. In my earlier filed application I disclose mechanism including coating cylinder and piston elements for effecting pressure fluid operated forward feed and retraction of a bit rotating motor, together with manual means for bodily advancing and retracting the bit rotating motor and its pressure fluid operated means. Associated with the bit rotating motor is a valve controlled by the torque of the motor for limiting the pressure at which the bit may be forced toward its work by either the pressure fluid operated means or the manually operated means. The drilling mechanism illustrated herein includes pressure fluid operated means and manually operated means similar to those shown in my earlier filed application for advancing or retracting the bit rotating motor, but associated with the bit rotating motor of this drilling mechanism is an electromagnetically operated valve having its winding connected in the motor circuit so that the operation of the valve for controlling the feeding pressure on the bit will vary in accordance with the load on the motor, as will be shortly pointed out.

Referring to the drawings, it will be noted that the drilling mechanism as a whole comprises bit rotating means generally designated 1, bit feeding means generally designated 2 and drill supporting and guiding means generally designated 3, all generally similar to those shown in my said copending application.

The drill supporting and guiding means comprises a trunnion member 4 having a swivel plate 5 adapted to be clamped in the saddle mounting of a suitable support. Formed in the trunnion

member is a bore which receives a tube 6, the latter fixed at its ends within portions 7, 7' depending from a support member 8. The tube 6 provides a swivel mounting for the support member 8 so that the bit rotating and feeding means may be moved into positions at the side of the drill hole, and a plunger lock 11, guided within bores in one of the depending portions 7, is received in a recess 12 in the trunnion member 4 for locking the support member 8 in an upright position.

The feeding means 2 comprises a feed cylinder 13 slidably guided in a bore 14 in the support member 8 and containing a reciprocable feed piston 15. Extending from the feed cylinder through packings 16 carried by a front head 17 of the feed cylinder is a tubular piston rod 18. A rear cylinder head 19 is suitably secured to the feed cylinder 13 and closes the rear end of the cylinder bore. Movement of the feed cylinder in the bore 14 of the support member is limited by engagement of the front and rear cylinder heads with the ends of the support member. Packings 20 on the feed piston sealingly engage the walls of the bore in the feed cylinder and are held in position by members 21 and 22 clamped on the rear end of the piston rod between a shoulder 23 and a plate 24, the latter secured to the piston rod, as by screws 26. Extending through the tube 6 and cylinder heads 17 and 19 is a tube 28 having threads 29 formed along a portion of its length. The threads 29 coact with the threads of a non-rotatable feed nut 30 carried by the support member 8. The tube 28 is fixed against axial movement relative to the feed cylinder by a split ring 32 seated in grooves in the forward end of the tube and in a plate 33 respectively, the latter being secured to the front cylinder head 17. Attached to the rear end of the feed screw tube 28 is a hand crank 34, and a spring-pressed plunger lock 35 is carried by the hand crank and is receivable within a recess 36 in the rear cylinder head 19 for locking the feed screw tube against rotation during automatic feeding of the drill.

Secured to the forward end of the piston rod 18, as by welding, is a head member 38, and attached, as by screws, to the head member is a control head 39. Threaded in an opening in the control head 39 in alignment with the feed screw tube 28 is a member 40 having a sleeve portion fitting within the bore of the feed screw tube 28, and secured to this sleeve portion, as by welding at 42, is a tube 43 having a sliding fit within the tube 28 and acting as a sliding guide for the drill.

The drill bit rotating means 1 comprises herein a high speed electric motor 45 having a stator casing 46 provided at its front and rear ends with heads 47 and 48 respectively, the parts being held in assembled relation and attached to the control head 39 by tie bolts 50. The motor has a usual field 51 and an armature rotor 52 keyed to a shaft 53 which is journaled in bearings supported in the motor heads. Electric energy may be conducted to the motor 45 from any convenient source through a connector plug 54 mounted on the control head 39 and wiring 55. A chuck 57 secured to the forward end of the motor drive shaft 53 receives the drill rod carrying the drill bit.

Referring to the means for supplying liquid under pressure to the hydraulic feeding means, it will be noted that there is provided in the control head 39 a liquid supply chamber 60 to which liquid under pressure is conducted through a

strainer 61 from a passage 62 formed in a member 63 attached, as by bolts, to the control head 39. Formed in the control head 39 in alignment with the feed screw tube 28 is a bore 65, and fixed within this bore is a ported valve bushing 66 having reciprocably mounted therein a control valve 67, as shown in Fig. 10. The control valve is of the spool type and has a rearwardly projecting valve stem 68 which extends into a recess in a rotatable member 69. A pin 70 extends through a transverse bore in the valve stem and has its ends guided in slots 71 in the member 69 to prevent rotation of the valve. A pin 72 extends through a transverse bore in the end of the valve stem, with its ends projecting into an annular groove 74 in the rotatable member 69 to lock the valve stem and the rotatable member against relative axial movement. The rotatable member 69 has a rearwardly extending portion 75 in threaded engagement with the sleeve portion of the non-rotatable member 40. The rear end of the portion 75 is rigidly secured at 76 to a tube 77 which extends centrally within the tube 43 and which is square in cross section. A control rod 78, which is also square in cross section, is telescopically arranged within the tube 28 at its rear end and is held against movement longitudinally of the tube 28 by a pin connection at 79 with a rotatable operating element 80 having an operating knob 81, the element 80 held as to axial movement by a retaining pin 82 secured within the hub of the handle 34 and passing through an annular groove 83 in the member 69. It will be seen that on rotating the control rod 78 the tube 77 and the member 69 will be rotated and, due to the threaded connection between the member 69 and the stationary member 40, moved axially, thereby effecting a movement of the valve 67 longitudinally of the valve bushing 66.

Communicating with the rear end of the bore of the valve bushing is an exhaust chamber 85 connected by a passage 86, as in Fig. 10, with a groove 87 in the head member 38, which in turn communicates with an exhaust passage 88, shown in Fig. 1. At the front end of the valve bushing is an exhaust chamber 89, and a passage 91, controlled by a reverse-flow-preventing check valve 92, connects this exhaust chamber with the exhaust passage 88. Surrounding the valve bushing are grooves 94 and 95 and a chamber 96, said grooves and chamber connected by ports 97, 98 and 99, respectively, with the bore in the valve bushing. The groove 94 communicates directly with the liquid supply chamber 60, as shown in Fig. 1. The groove 95, as shown in Fig. 1, is connected by a passage 101 in the control head with a passage 102 in the head plate 38, the latter passage communicating with the interior of the feed piston rod 18. A port 103 in the feed piston rod connects the interior of the piston rod with the feed cylinder bore at the front side of the feed piston 15. The chamber 96, as shown in Fig. 8, is connected by a passage 105 to a chamber 106 which communicates, under the control of an electromagnetically operated valve generally designated 107, with a passage 108, as shown in Fig. 3. The passage 108 communicates with a passage 109 in the head plate 38 (Fig. 5) which opens into a recess 110, the latter being connected by a tube 111 with the cylinder bore at the rear side of the feed piston 15. Formed in the outer periphery of the valve 67 are grooves 114 and 115 communicating with an axial chamber 116 in the valve through radial ports 117 and 118 respectively. At the forward end of the

valve is a recess 120 communicating with the exhaust chamber 80, and opening through the walls of the valve into this recess are ports 121. When the valve is in the position shown in Fig. 10, the groove 115 connects the grooves 94 and 95 through the ports 97 and 98 so that liquid under pressure may flow from the supply chamber 88 to the forward side of the feed piston and effect a retraction of the drill bit from the work. At the same time, the chamber 86 is connected through ports 99 with the exhaust chamber to vent liquid from the feed cylinder bore at the rearward side of the feed piston. When the valve 67 is moved into its extreme position to the left of that shown in Fig. 10, the supply groove 94 is connected through the groove 115, ports 118, chamber 116, ports 117, groove 114, and ports 99, to the chamber 86 so the liquid may flow to the feed cylinder bore at the rearward side of the feed piston and effect a forward feed of the drill bit. At this time, the groove 95 communicates directly with the exhaust chamber 85 past the end of the valve 67 to vent liquid from the feed cylinder bore at the forward side of the feed piston. When the valve is moved into a position between its two extreme positions, the chamber 86 and the groove 95 are connected to the exhaust chambers 86 and 85 respectively by way of the ports 99, the ports 121 and chamber 120, and past the right-hand end of the valve 67, to vent liquid from the feed cylinder bore at both sides of the feed piston.

Referring to the improved electromagnetically operated valve 107, see Fig. 3, it will be noted that received in stepped bores 124 and 125 formed in alignment with each other in the control head 39 and transversely thereof, is a sleeve 126 having a portion 127 fitting the bore 124 and a portion 128 of reduced diameter fitting the bore 125. Received within the sleeve portion 127 is a coil 129 to which current is supplied by leads 130 connected in the circuit of the motor 45 in such a way that the current through the coil varies directly with the load on the motor, increasing as the motor load increases. For example, the coil may be placed in series with the armature. A cover plate 131 fits over the outer end of the sleeve 126, and the cover plate and sleeve are held firmly in place, as by bolts 132. Threaded within the inner end of the sleeve portion 128 is a plug 133 having an opening for slidably receiving a rod 135 which extends axially of the bores 124 and 125. At one end of the rod 135 is a plunger-like portion or armature 136 extending through the open center of the coil 129 and at its outer end, and for as much more thereof as is desirable, formed of a suitable magnetic material. A coiled spring 137 surrounds the rod 135 and acts against the plug 133 and a shoulder 138 on the rod so as to urge the plunger portion continuously in a direction towards the cover plate 131. Slidably fitting on a reduced portion 140 of the rod 135 is a valve sleeve 141 which also has a close sliding fit within a bore 142 in the control head that opens into the chamber 106. A coiled spring 143 surrounds the reduced portion 140 and acts against a shoulder 144 on the rod and the inner end of the sleeve 141 to urge the latter continuously towards an enlarged head piece 145 fixed to the end of the reduced portion in any suitable manner. Formed on the sleeve 141 is an end-seating valve portion 147 for engaging a seat 148 formed on the control head around the opening between the chamber 106 and the passage 108. 70

Between the sleeve 141 and the rod portion 140 is an annular space 150 connected at its inner end by a radial passage 151 to a chamber 152, and the latter is connected, as shown in Fig. 9, through passages 153 and 154 to the groove 87, which communicates with the exhaust passage 88. It will be noted that when the sleeve 141 is held against the head piece 145 the annular space 150 is closed against communication with the passage 108, but when the valve portion 147 of the sleeve engages the valve seat 148 and the rod 135 is moved further to the right, as shown in Fig. 7, the passage 108 is placed in communication with the space 150 and liquid is vented from the rear end of the feed cylinder.

Formed in the control head 39, as shown in Fig. 3, are aligned bores 156 and 157 extending transversely and at opposite sides of the control head. Arranged in the bore 156 is a manual control valve 158 which is adapted to control the flow of liquid under pressure to one side of a diaphragm 159 (Fig. 5) which controls the actuation of a motor control switch 160. Arranged in the bore 157 is a manual control valve 161 which controls the supply of liquid under pressure through the power shaft of the motor and rod line to the drill bit. The control valves 158 and 161 and the motor control switch 160 are fully described in my copending application Serial No. 268,792, and further description of the same herein is herein unnecessary.

The mode of operation of the improved drilling apparatus is as follows: The apparatus is clamped in position on a suitable support at the working face and the valve 67 is then moved into a position, by manipulating the control handle 81 of the valve, to supply liquid under pressure to the rear end of the feed cylinder and effect forward feed of the drill motor. When the drill bit reaches a position to start drilling, forward feed will be momentarily interrupted, the valve 161 will be operated to effect a supply of drilling liquid to the drill bit, liquid will then be supplied to the diaphragm 159 to operate the motor control switch and start the motor, and then the valve 67 will again be adjusted to supply forward feeding fluid. Assuming that the load on the drill motor is low, the current flowing through the motor and the coil 129 will be low and the spring 137 will hold the plunger 136 against the cover plate 131 (Fig. 3). At this time the valve portion 147 of the sleeve 141 is held from the valve seat 148, and liquid will be supplied past the valve 67 to the chamber 86, through the passage 105, and past the valve seat 148 to the passage 108, where it is conducted to the passage 109 and tube 111 leading to the rear end of the feed cylinder. The pressure at which liquid is supplied to the rear end of the feed cylinder is sufficient to move the drill bit against the work, under certain drilling conditions, and to overload the bit rotating motor 45. As the load on the motor increases, the current through the coil 129 increases, and the magnetic force on the plunger 136 increases and will ultimately effect movement of the rod 135 in a direction to seat the valve portion of the sleeve 141 and shut off the flow of liquid to the feed cylinder. As the valve portion 147 approaches its seat the flow of liquid will be reduced and the forward feed slowed down, and when the flow of liquid is completely cut off the feeding pressure is immediately removed since there is no expansion of the liquid. If it is desired to feed the feed cylinder forward within its guide bore relative to the trunnion member 4

during forward feeding of the drill bit by liquid acting on the rear pressure area of the feed piston, the operator need only turn the hand crank of the feed screw so as to advance the feed cylinder and increase the feeding pressure on the drill bit. If the hand crank is turned at such a rate that the feeding pressure on the drill bit continues to increase the load on the bit rotating motor even after the end of the sleeve 141 engages the valve seat and cuts off the supply of liquid to the feed cylinder, then the current through the coil 129 will increase and cause the rod 135 to be moved to the right to a position as shown in Fig. 7, so that passage 108 is placed in communication with the space 150 to vent liquid from the rear end of the feed cylinder and permit the feed cylinder to be moved forward relative to the feed piston. The venting function is at all times under the control of the electromagnet, the magnetic force of which varies with the load on the motor, so that varied rates of venting, adapted to different rates of cylinder movement, are obtained; and if the feed exhaust passages are of sufficient capacity the speed at which the operator manually feeds the feed cylinder forwardly can not dangerously overload the bit rotating motor or cause undue heating of the bit. After the feed cylinder has been advanced so that the rear cylinder head abuts the rear end of the feed piston, if manual feeding pressure were to continue to be applied by further movement of the hand crank, the bit rotating motor might conceivably be overloaded or stalled, but such an occurrence is improbable. This automatic manual feeding operation enables the drill bit to be fed forwardly the combined distances of travel of the feed piston in the feed cylinder and the feed cylinder relative to the trunnion support without any manual readjustment of the drill motor or its controls.

As a result of this invention, there is provided an improved drilling apparatus having improved means for controlling the feeding pressure on the drill bit. It will be noted that by means of the improved feed control means the feeding pressure is varied directly in accordance with the load on the drill motor. It will also be evident that there is provided with the drilling apparatus improved manual means and pressure fluid actuated means for subjecting the drill bit to a feeding pressure, and that by reason of the improved feed control means the resulting feeding pressure on the drill bit is automatically controlled. It will further be evident that there is provided an improved electromagnetically controlled valve means that is responsive to the load on the drill motor for controlling the feeding pressure on the drill bit. By reason of the improved feed control means there may be obtained an automatic or manual feeding of the drill bit and a repositioning of the feeding elements at any time. Other uses and advantages of the improved drilling apparatus will be clearly apparent to those skilled in the art.

While there is specifically described one form which the invention may assume in practice, it will be understood that this form of the same is shown for purposes of illustration and that the invention may be modified and embodied in vari-

ous other forms without departing from its spirit or the scope of the appended claims.

What I claim as new and desire to secure by Letters Patent is:

- 5 1. In a drilling apparatus, in combination, a motor for rotating a drill bit, fluid actuated feeding means for the drill bit, valve means for controlling the flow of fluid under pressure to said feeding means, valve means for controlling the 10 venting of fluid from said feeding means, electromagnetic means varying in strength within certain predetermined limits in accordance with certain load changes on said motor for controlling said first mentioned valve means, and said electromagnetic means increasing in strength over said 15 predetermined limits when said load changes on said motor are exceeded for controlling said second mentioned valve means to effect venting.
2. In a drilling apparatus, in combination, a 20 motor for rotating a drill bit, fluid actuated feeding means for the drill bit, valve means for controlling the flow of fluid under pressure to said feeding means, electromagnetic means for controlling said valve means, said electromagnetic means varying in strength in response to load changes on said motor within certain predetermined limits and operative to effect closure of said valve to interrupt fluid flow to said feeding means when the load on said motor reaches the higher 25 limit, and means associated with said valve means and controlled by said electromagnetic means for venting fluid from said feeding means upon loading said motor a predetermined amount beyond the higher one of said load limits.
3. In a drilling apparatus, in combination, a 30 motor for rotating a drill bit, fluid actuated feeding means for said motor, means associated with said fluid actuated feeding means for manually feeding said motor, a valve for controlling the flow 35 of fluid under pressure to said fluid actuated feeding means, means including a valve for venting fluid from said feeding means, and electromagnetic means responsive to the load changes on said motor for controlling said first and second 40 mentioned valves, thereby regulating the feeding pressure on the drill bit.
4. In a drilling apparatus, in combination, a 45 motor for rotating a drill bit, fluid actuated feeding means for said motor, means associated with said fluid actuated feeding means for manually feeding said motor, means including an electromagnet responsive to the load changes on said motor and operative at a predetermined motor load for automatically interrupting the flow of 50 fluid to said feeding means, and associated means actuated by said electromagnet on loading said motor by said manual feeding means in excess of said predetermined motor load, for venting fluid from said feeding means.
5. In a drilling apparatus, in combination, an 55 electric motor for rotating a drill bit, fluid actuated feeding means for said motor, means for controlling the supply of fluid to said feeding means and including means responsive to the current flowing in the circuit for said motor, and means associated with said controlling means for venting fluid from said feeding means when the current in the motor circuit exceeds a predetermined value.

WIN W. PAGET.
